ANTI-WHEEL-LOCK SYSTEM

Clarence Floyd Hirshfeld, Detroit, Mich., and Alexander H. Brown, New York, N. Y., assignors, by mesne assignments, to Transit Research Corporation, New York, N. Y., a corporation of New York

Application February 21, 1935, Serial No. 7,587

13 Claims. (CL 303—21)

This invention relates to automatic means operative during the application of braking pressures to wheels or drums connected to wheels to prevent locking of the wheels during linear travel 5 of the vehicle.

A principal object of the invention is to employ a combination of electrical and mechanical means, for the above purpose, which will act to release the brakes in response to a tendency of 10 a wheel to skid and before actual locking of the wheel occurs together with means controlled by and responsive to a time delay device to re-apply the brakes. The re-application of the brakes is therefore independent of wheel and track 15 relation.

Another object is to provide means, as above described, which will act to-apply, release and re-apply the brakes a successive number of times during a single manually controlled application 20 of braking pressures to the wheels without materially decreasing the efficiency of the brakes to stop the vehicle in a given linear travel.

In the case of a rail wheel of conventional size and weight it will be understood that when a 25 wheel begins to slip prior to locking and the brakes are released whereby it becomes free to gain angular speed, an interval of time of the order of $\frac{1}{10}$ to $\frac{1}{5}$ of a second is necessary for this to happen because of the inertia of the wheel. It 30 will also be understood that the closing of valves and building up of braking pressures for re-application of the brakes also necessarily consumes an appreciable time so that if the train of mechanism were dependent for re-application upon a 35 restoration of the wheel to a definite angular speed many feet of linear travel would be lost. It is therefore another object of this invention to provide release and re-application means operative in accord with a time interval in such manner that functioning of the train of re-application means over-laps the period of releasing whereby total free releasing is attendant with an 40 immediate response by the re-application means, the actual time interval being no longer than is 45 theoretically and actually necessary.

A further object is to provide means for setting the time delay mechanism, as desired, together with means convenient to the hand of an operator for selecting any one of a plurality of these 50 predetermined settings.

A further object is to provide a release and re-application means, as described, for each individual axle so that any three axles of a conventional street car, for instance, are independent 55 of a possible failure of brakes on any one axle.

A further object is to provide a number of other safety factors in contemplation of a trolley leaving the power line, derailing, etc., all of which will become hereinafter more fully apparent as reference is had to the accompanying drawings 5 wherein my invention is illustrated, diagrammatically, by way of example, and in which—

Figure 1 is a diagram illustrating the electrical control circuits, and the fluid braking mechanism; 10

Fig. 2 is a vertical axial section of an inertia switch;

Figs. 3, 4 and 5 are detail sections taken respectively on lines 3—3, 4—4 and 5—5 of Figure 2;

Fig. 6 is an axial cross section illustrating the 15 assembly of the inertia switch on a vehicle part;

Fig. 7 is a diagram of the device consolidated into a unit for controlling all brakes on a two truck rail car, and

Figs. 8 and 9 are diagrams for explanatory 20 purposes.

With reference first to Figure 1, a core 1 having a winding W_1 is connected in series with a resistor R_1 and manual switch S_1 to a source 2 of electrical energy, the winding W_1 being grounded at 25 3 and the source 2 being grounded at 4. In parallel with the winding W_1 is a condenser C_1 and a line 5 extending from a point in advance of winding W_1 to the ground 3 in order to short circuit the winding W_1 . In the line 5 is a switch S_2 which, upon opening, interrupts the short circuit and as a result, the voltage in the circuit is impressed upon the winding W_1 . The switch S_2 is inertia operated as will be hereinafter more 30 fully described.

Also connected to the electrical source 2 is a line 6, 6a, a resistance R_4 , a switch S_3 , and a line 7 grounded at 8. In the line 7 is a winding W_3 having a core 9. An armature A_1 opposite the core 1 and subject to a spring 10 normally holds the switch S_3 in an open position. A condenser C_2 is interposed between the resistance R_4 and the line 7 and in parallel with the switch S_3 . 35

Also electrically associated with the core 1 is a second winding W_2 constantly energized by the line 6 which has one side grounded at 3 and the other side connected to the source 2 through a resistance R_2 and a resistance R_3 manually variable in magnitude by a suitable means such as a two throw switch S_4, S_5 . The resistance R_3 40 and switch S_4, S_5 provide for quick manual adjustment of control current to either one of two different predetermined values for a purpose 45 which will be hereinafter pointed out.

The brake applying means as herein illus- 50

trated is of the pneumatic type but other systems may be equally well used. As illustrated, the numeral 11 designates a wheel and 12 a brake shoe connected by a rod 13 to a piston 14 in a fluid actuator cylinder 15. In the cylinder 15 is a brake take-off spring 16 for the shoe 12. A conduit 17 connects the cylinder 15 into a casing 18 which has a restricted central portion 19 provided with a valve seat 20 thereby dividing the interior 10 of the casing into two chambers, 21 and 22. The upper chamber 21 has an outlet port formed with a valve seat 23 which communicates through a conduit 24 with a manually controlled supply line 25 through which fluid pressure is transmitted to 15 the piston 14 and the brake 12. The pressure of the fluid is controlled in any suitable manner by an operator. Slidably received in the chamber 22 is a piston 26 having a stem 27 extending past the valve seat 20. Integral with the stem 27 is 20 a valve 28 for the seat 20. The stem 27 also carries a valve 29 for the valve seat 23 which is so spaced from the valve 28 that only one of said valves may be seated at one time. A spring 30 urges the valve 28 towards its seat 20 and likewise 25 opposes the closing of the valve 29. The chamber 22 has an exhaust outlet 31, and a feed conduit 32 from a casing 34. A ported wall 35 divides the interior of the casing 34 into two chambers 33 and 36. The port in the wall 35 30 constitutes a valve seat 38 for a valve seating toward the chamber 33. The upper wall of this chamber 33 is provided with an exhaust outlet 37 formed as a valve seat and alternate valves 39 and 40 connected by a stem 41 are provided for 35 the seats 38 and 37 respectively. A spring 42 urges the valve 39 to a seating position and urges the valve 40 from its seat.

Integral with the valves 40 and 39 is a rod 43 projecting outwardly of the casing 39 for pivotal engagement by an armature A₂ subject to the core 9, hereinbefore described.

In Figures 2 to 6 inclusive a suitable inertia switch S₂ is illustrated in detail. The switch comprises a housing 50 which is illustrated as being mounted on a transmission housing 51 containing an axle 52 which is journaled in two wheels 11 of the vehicle.

It could be mounted in other suitable places as is evident to one skilled in the art. As now used, the combination is with hypoid gears with 50 the propeller shaft leading into the front end of the transmission housing and the pinion for my device coaxial with the propeller shaft and mounted at the rear of the housing. This pinion therefore functions just as though it were 55 mounted directly on the end of the propeller shaft in case worm gearing instead of hypoid gearing were employed. Thus, a gear 53 on the axle 52 is in constant engagement with a pinion 54 on a propeller shaft 55. Rotatably mounted in the 60 housing 50 is a shaft 56 detachably connected by an element 56a to a gear 57 which constantly meshes with the gear 53 whereby the shaft 56 rotates in unison with the axle 52. Between the housing 51 and the housing 50 is a disk 58 supporting an oil seal 59 which excludes lubricating oils, contained in the transmission housing, from the switch housing. Rotatably supported on the shaft 56 by an anti-friction bearing 60 is a flanged drum 61 having a stud 62 radiating inwardly from the peripheral flange thereof. One end of a coil spring 63 is attached to the stud 62 and the other end is attached at 64 to the shaft 56.

A disk 66 of insulating material extends into 75 and is keyed to the shaft 56 being clamped on the

end of shaft 56 by a nut 65. The disk is recessed at 67 to receive contact fingers 68 and also at 69 to receive the above described stud 62 and another similar stud 70. The studs 62 and 70, as more clearly shown in Figure 4, serve as means 5 for limiting rotation of the drum 61 relative to the disk 66 and shaft 56. Contactors 71 also radiate inwardly from the flange of the drum 61 and extend into the recesses 67 to cooperate with the contact fingers 68. These contactors 71 are 10 normally maintained in engagement with the contact fingers 68 by the action of the coil spring 63.

The contact fingers 68 are electrically coupled by conducting elements 72 to a ring conductor 73 fixedly mounted on and insulated from the shaft 15 56. Brushes 74 are slidably supported by stationary brackets 75 and resiliently urged by springs 76 into contact with the ring 73. Wire conductors 77 connect the brushes 74 to a stationary terminal post 78 to which the line 5, forming part of the 20 diagram shown in Figure 1, is connected. The drum 61 is grounded through its supporting bearing 60 and the torsion spring 63.

In describing the operation of the device it will be assumed that the wheel 11 is rotating and 25 that fluid under pressure is being supplied through the conduits 25 and 24, chamber 21 and conduit 17 to the cylinder 15 to actuate the piston 14 and the brake shoe 12 into engagement with the wheel 11. The initial pressure in the line 25 may be 30 initiated by a foot pedal, a hand lever or any system partially automatic subsequent to initiation by the operator of the vehicle. The term "manually controlled" as hereinafter to be used is intended to include any means subject to the 35 will of the operator. If the deceleration of the wheel 11 is greater than can exist with normal braking so that the wheel begins to slip the inertia reaction of the drum 61 overcomes the torque of the spring 63 and rotates relative to the disk 66. 40 Rotation of the drum 61 carries the contactors away from the contact fingers 68 thereby interrupting the circuit from the line 5 to the ground. Switch S₂ is thus opened and it remains open until the spring 63 overcomes the inertia of the 45 drum 61 thereby returning the contacts 71 to contact with the fingers 68.

Referring again to Figure 1, when the switch S₂ is opened the full line voltage is impressed on the winding W₁ and the resistance R₁ in series so 50 that current from the electrical source 2 flows through the resistance R₁ and winding W₁ to the ground 3, thus fully energizing the winding W₁ and inducing a magnetic flux in the core 8 which attracts the armature A₁ and closes the switch S₃ 55 instantaneously. The switch S₃ is in series with the resistance R₄ and the winding W₃ so that when it is closed current from the electrical source 2 flows through the line 6, resistance R₄, switch S₃ line 7 and the winding W₃ to the ground 8. 60 A flux is thus induced in the core 8 which attracts the armature A₂, causing it to depress the rod 43 thereby seating the valve 40 and unseating the valve 39. Inasmuch as the chamber 36 is in 65 constant communication with the conduit 25, through which braking pressure is supplied, unseating of the valve 39 permits fluid under pressure to pass from the chamber 36 to the chamber 33, from which it is conducted by the conduit 32 to the chamber 22. The pressure in the chamber 70 22 actuates the piston 26 to unseat the valve 28 to seat the valve 29 since the piston has a greater bottom surface area than the top of the valve 28. The cylinder 15 and conduit 17 are thus opened to the exhaust port 31 whereby the fluid pressure 75

in the cylinder 15 is rapidly dissipated and the brake is accordingly released.

Upon release of the brake the wheel 11 will cease its excessive angular deceleration and will thereafter resume normal rolling. The spring 63 will thereupon rotate the drum 61 relative to the disk 66 bringing the contactors 11 to re-engagement with the contact fingers 68, thus closing the switch S₂ to short circuit the winding W₁.

Stated briefly, the operation to this point is as follows: excessive deceleration of the wheel 11 results in an opening of the switch S₂ and release of the braking pressure in the line 17. The distinction between "slipping" and "locking", as herein used, is important. Slipping is the condition where the wheel has lost traction with the rail but is still turning and hence presenting a constantly changing area to the rail. Locking is the condition where the wheel has completely ceased rotation and hence carries its portion of the weight of the vehicle on a small unchanging wheel tread area by skidding. Locking causes flat spots on the tread and hence it is this condition that applicants seek to avoid. The releasing, as hereinbefore described, will take place in response to slipping and before locking occurs. This may not be strictly true where the linear velocity of the wheel is very small when initial braking occurs, as in this case an actual locking may possibly occur before release, but it is true, with this exception.

When the switch S₂ again closes and short circuits the winding W₁ and, after a time interval determined by the inductance of W₁ the resistance of W₁ and the initial current of W₁, the current through the winding W₁ decays to zero, and with it the magneto motive force due to W₁ inducing a flux in the core 1. As the flux core 1 fades it reaches a point at which the spring 10 moves the armature A₁ away from the core 1 and coincidentally opens the switch S₃. This absorbs a time interval many times longer than the time of closing for this reason: after the switch S₃ is closed the air gap between the armature A₁ and the core 1 is much smaller and it takes less magnetic flux to hold it closed than it did to start it closing. Therefore the current through W₁ can be reduced considerably after S₃ is closed before the spring 10 can pull it off the core 1. When the inertia switch S₂ is closed the current flowing around in W₁ can then flow around in a circle through W₁ and S₂ without having to pass through R₁. Thus the reason for the delayed opening of S₃ upon closing S₂ is that current flowing through W₁ does not have to pass through R₁. This system as we have built it provides a time delay of approximately seven and a half times as long to open S₃ as to close it. When the switch S₃ is opened the current flow through the winding W₃ is interrupted and the armature A₂ is pushed away from the demagnetized core 9 by the action of the spring 42.

At this stage of the operation the valve 39 is seated and the valve 40 is unseated so that the fluid under pressure may exhaust from the chamber 22 through the conduit 32 and port 37. The spring 30 seats the valve 28 and directs the fluid under pressure from the conduit 24 to the cylinder 15 thereby re-applying the brake.

It will be understood from the foregoing that a loss of excessive angular deceleration is instantly followed by the beginning of the brake re-application cycle of operations and the instant of actual application is subject to control

by a definite and predetermined interval of time. This is the essence of my invention and is highly important for the following main reasons: first, the wheel 11 is heavy and hence its inertia can not be overcome without the lapse of time. If brake re-application should follow brake release in too rapid succession it is conceivable that the wheel might eventually lock. On the other hand, if re-application were delayed for any time interval after the wheel resumed rolling then the release device would lengthen the distance through which the vehicle must travel before the brakes can bring it to a stop. It is thus essential to ideal operation that the factor time control the operation. With this system, the beginning of energization of the train resulting in re-application may be initiated before the wheel actually begins to roll. In fact, applicants prefer this.

In order to provide flexibility of control, it is desirable to be able to vary this time factor which must elapse before brake re-application. Up to this point the circuit 2, 6, S₄, S₅, R₃, R₂, W₂, 3 has not been mentioned with regard to its effect on operation. This circuit may be suitably added for the purpose of giving a further control of the time delay element. This circuit is constantly energized since it is intended that the two-way switch S₄, S₅ be closed on one side or the other at all times. For instance, this switch may be placed convenient to the motorman or operator so that he can quickly change from a "dry rail setting" to a "slippery rail setting" since it requires more time to get the wheel 11 rolling again after it has once started to slip on a slippery rail than it does on a dry rail. Bare-side resistor tubes R₃ are suitable for shop adjustment of the contacts as indicated by the arrows.

The further control of the time after the switch S₂ closes before the switch S₃ opens is obtained by thus superposing on the magneto motive force of the winding W₁ the magneto motive force of the winding W₂ where the magneto motive force of W₂ acts in the opposite direction to that of W₁. When W₁ is energized its magneto motive force is larger than that of W₂ which remains energized continuously, and as the current dies in W₁ there is a point where its magneto motive force drops down to that of W₂ which makes it possible to reduce the net magneto motive force acting on the core 1 to zero before the current through W₁ drops to zero. The time required to reduce the net magneto motive force in the core and hence the net flux is evidently subject to control by changing the constant value of the magneto motive force due to W₂ which can easily be accomplished by changing the current through W₂ by means of the rheostat R₃. The effect of this circuit is seen in Figs. 8 and 9. In Fig. 8, the flux in the core 1 just after S₂ opens due to the winding W₁ is indicated as "W₁ Flux" and in Fig. 9 the flux in the core 1 just after S₂ closes due to W₁ is indicated as "W₁ flux". The flux in the core due to W₂ is constant because W₂ is constantly energized. The net flux in both instances is the difference between that induced by W₁ and W₂ from which it is seen that a slight change in the magnitude of the flux induced by W₂ changes the time at which the net flux becomes zero much more effectively in closing (Fig. 9) than in opening (Fig. 8). This method of showing the effect of the bucking coil is not exhaustive but is correct to show the effect graphically.

The condensers C_1 and C_2 are used to reduce the intensity of the arcs when the switches S_2 and S_3 , respectively, are opened.

- 5 In the interest of safety it will be noted that one terminal of each of the windings W_1 , W_2 and W_3 , is grounded, and that when there is no current flowing through winding W_3 the spring 42 and the fluid pressure in the line 25 both act in the same direction to close the valve 10 39. This insures normal braking action in the event that the trolley pole leaves the wire rendering the entire circuit inoperative. Further, the switch S_1 constitutes a safety precaution and may be opened by the motorman or operator 15 in the event of the highly improbable condition where the armature A_1 is held closed by the constant current in the winding W_2 .

In Figure 7 the diagram illustrated in Figure 1 has been consolidated to equip each axle of a rail vehicle with an individual apparatus for controlling the brakes. For the purpose of understanding the apparatus shown in this view, attention is directed to the detailed description and illustration of Figure 1, the same reference numerals being applied to this figure as are employed in connection with Figure 1. The vehicle is shown as having four axles, designated I, II, III and IV and the respective circuits, individual to each axle, may be traced throughout the diagram by the reference characters of the axles which they control. For example a group of four adjustable resistances R_2 are illustrated and the resistance I is in the circuit controlling the axle I, resistance II in the circuit controlling the axle II, resistance III in the circuit controlling axle III, and resistance IV in the circuit controlling axle IV. The same procedure is followed throughout the entire diagram.

What we claim is:

- 40 1. In combination in a vehicle including wheels and an axle and manually controlled means for applying brakes thereto, automatic means for releasing said brakes subsequent to a slipping of said wheels, a time delay device, automatic means 45 subject to said time delay device and responsive to the automatic releasing means for re-applying said brakes, and manual means for altering at will the time factor introduced by said time delay device.
- 50 2. In combination in a vehicle having wheels, axles and manually controlled brake applying means, an electric circuit having a winding therein, a core for said winding, an armature subject to actuation by said core upon energization, a 55 second circuit including a switch connected to said armature for closing upon actuation of said armature by said core, an armature subject to said second circuit for causing release and re-application of said brake upon energization and de- 60 energization respectively of said circuits, and automatic means comprising an inertia switch responsive to rate of axle rotation for controlling energization and de-energization of said circuits.
- 65 3. In combination in a vehicle having wheels, 65 axles and manually controlled brake applying means, an electric circuit having a winding therein, a core for said winding, an armature subject to actuation by said core upon energization, a second circuit including a switch connected to 70 said armature for closing upon actuation of said armature by said core, an armature subject to said second circuit for causing release and re-application of said brake upon energization and de-energization respectively of said circuits, and 75 an inertia switch sensitive to initial slipping of

one of said wheels for energizing said circuits and sensitive to the loss of excessive angular deceleration by said wheel for de-energizing said circuits.

4. In combination in a vehicle including wheels and an axle and manually controlled means for applying brakes thereto, automatic means for releasing said brakes in response to initial slipping of said wheels, said means comprising an electric circuit, armature means associated with the brake applying means and an inertia switch instantly sensitive to excessive angular deceleration of the wheels for energizing said circuit whereby said armature means is actuated to release said brake applying means, and means responsive to the loss of excessive deceleration by said wheels upon release of said brakes for re-applying said brakes.

5. In combination in a vehicle including wheels and an axle and manually controlled means for applying brakes thereto, automatic means for releasing said brakes in response to initial slipping of said wheels, said means comprising an electric circuit, armature means associated with the brake applying means, and an inertia switch instantly sensitive to excessive angular deceleration of the wheels for energizing said circuit whereby said armature means is actuated to release said brake applying means, said inertia switch de-energizing said circuit upon loss of excessive angular deceleration by said wheels, means for actuating said armature to reestablish the application of said brakes upon de-energization of said circuit, and a time delay device including the inductance of a winding having a core magnetized by the current flow in said circuit for delaying for an appreciable period of time the actuation of said armature to re-establish brake application.

6. In combination in a vehicle including wheels, an axle and manually controllable means for applying brakes thereto, automatic means for releasing said brakes in response to initial slipping of one of said wheels, said means comprising two electric circuits, an inertia switch associated with the wheels for directly establishing a full current flow through one of said circuits, a winding having a core therein also in the circuit controlled by 45 said inertia switch, a switch in the other of said circuits adapted for actuation to closed position by said core upon energization of said circuit, a second winding having a core therein in said second circuit, an armature for said second core 50 and means associated with said armature for releasing said brakes upon energization of said second circuit, and means for re-applying said brakes comprising said inertia switch which is adapted to interrupt the current flow thereby demagnetizing the core in said first circuit, spring means for opening the switch in said second circuit whereby said second core is de-magnetized, and spring means for affecting re-application of said brakes upon release of said armature by said second core. 60

7. In combination in a vehicle including wheels, an axle and manually controllable means for initially controlling the application of braking pressures to said wheels, an electric circuit, a winding having a core in said circuit, armature means subject to said core for releasing said braking pressures upon energization of said circuit, inertia means sensitive to initial slipping of either of said wheels for energizing said circuit, and means for de-energizing said circuit and for 70 re-applying said braking pressures subsequent to release thereof, said last named means comprising said inertia means and the inductance of said winding in opposing discontinuation of the current flow, a constantly energized bucking coil 75

around said core of less maximum magneto motive force capacity than said winding and a return spring attached to said armature.

8. The combination as set forth in claim 7 together with rheostat means convenient to the operator of the vehicle for varying the current through said bucking coil.

9. The combination as set forth in claim 7 together with variable resistor means for controlling the intensity of current flow through said bucking coil, and a single pole multi-throw manual switch convenient to the operator of the vehicle for quickly selecting a given number of settings of said resistor means.

10. In combination in a vehicle including wheels, an axle and manually controllable means for controlling the application of braking pressures to said wheels, an electric circuit including in series a resistance and a winding having a core therein, an inertia switch and a ground for said circuit in parallel with said winding and connected into said circuit between said resistance and said winding, said switch being normally closed whereby said circuit is normally short circuited around said winding, a second circuit having a resistance, a second switch and a second winding in series therein, a second core for said second winding also having a core therein, armature means connected to said second switch and subject to said first core for closing said circuit and energizing said second winding upon opening of said normally closed switch to energize said first circuit, armature means subject to said second armature for releasing the braking pressures against the vehicle wheels upon energization thereof, return springs connected to each of said armatures for return to normal position thereof upon de-energization of said cores, said first switch comprising an inertia device operative in response to the slipping of a wheel to open said first circuit, and a third circuit constantly energized and having a winding for said first core having a magneto motive force impressed thereon in opposite direction to that of said first winding whereby to affect the time of operation of said second armature following an actuating movement of said inertia controlled switch.

11. In combination with a vehicle including wheels, an axle and means subject to the will of the vehicle operator for initially controlling the application of braking pressures to said wheels, a grounded electric circuit, a resistance and a coil having a core therein in series in said

circuit, an inertia switch sensitive to excessive rate of deceleration of one of the wheels connected into said circuit between said winding and said resistance in parallel with said winding, a second circuit having a resistance and a switch therein, armature means adjacent said core connected to said last named switch for closing said switch against a spring upon substantially full energization of said core by the opening of said inertia switch, means responsive to the energization of said second circuit for releasing the brake pressures against the resistance of a second spring, said inertia switch being adapted to close and thereby to short circuit said coil upon loss of excessive deceleration by said wheel whereby the magnetic flux in said core fades, the spring of said armature and the spring of said spring-pressed means functioning to interrupt said second circuit and to restore said brake pressures respectively as the flux in said core fades to an amount less than the force exerted by the spring opposing closing of said armature means.

12. The combination of brakes, manual means for applying said brakes, mechanical means operative to release and reapply said brakes during application of said manual means, and an electrical circuit having armature means therein for actuating said mechanical means, said electrical circuit functioning instantaneously in response to abnormal angular deceleration of the device to which said brakes are applied to release said brakes, said circuit actuating said mechanical means to reapply said brakes upon loss of excessive deceleration by said device, said circuit having a time delay device therein whereby it lags in actuating said device to reapply said brakes.

13. The combination of vehicle brakes, manual means for applying said brakes, mechanical means operative to release and to reapply said brakes during application of said manual means, an electrical circuit having an armature therein for actuating said mechanical means, an inertia switch for short circuiting said circuit, said switch being adapted to open instantaneously in response to abnormal angular deceleration of one of the axles of the vehicle to energize said circuit thereby releasing said brakes, said switch closing immediately upon loss of excessive deceleration of said axle thereby interrupting said circuit, a time delay device operative immediately subsequent to the breaking of said circuit to delay the re-application of said brakes.

CLARENCE FLOYD HIRSHFELD.

ALEXANDER H. BROWN.
